DISPLAY RECEPTACLE

Chester E. Fussner, Cleveland, Ohio

Application December 22, 1934, Serial No. 758,816

6 Claims. (Cl. 206—44)

This invention has to do with the merchandizing of cakes, cookies, and the like, in stores, the invention involving primarily an attachment device applicable to the ordinary boxes or receptacles, in which the cookies, or cakes, etc., are usually contained, and from which they are vended to the purchaser.

The purpose of the invention has been to supply a simple attachment means in the form of a holder applied to the window, door, or cover of the box, or receptacle, for containing the cookies, cakes, etc., the said holder consisting of a readily attachable and detachable guide frame in which is mounted a slideable tray. The holder is designed so that the said tray may readily slide thereon, the tray providing a display container for the articles to be sold, and additionally, providing a container located at the windowed cover so that notwithstanding the depletion of the contents of the main box or receptacle for the articles to be sold, so long as the tray remains full, the display of the main box or receptacle with the full tray gives the impression that the main box is full of the articles, cookies, cakes, or whatever they may be. In other words, the display feature of the invention is useful because it gives the impression to the purchaser that the main container or box is full of fresh cookies, cakes, etc., notwithstanding that the contents of the said receptacle may have been greatly depleted.

An additional advantage of the invention in reference to the slideable mounting of the tray in the holder or guide frame lies in the fact that the tray may be moved or slid to a position extending away from the cover or top of the receptacle, and thus render accessible the contents of the tray so that they may be sold if desired, especially when there are not sufficient cookies or cakes in the main receptacle to fill the order of the purchaser.

Another feature of the invention of importance has been to so design the holder or guide frame for the display tray that it may be very quickly applied to containers of the conventional type at present in use without modification of the construction of the latter in any way.

Other advantages of the invention will appear more fully as this description proceeds, and in the accompanying drawing.

Figure 1 is a perspective view of an ordinary merchandising box or receptacle for cookies, having the invention applied thereto.

Figure 2 is a cross sectional view of the upper

portion of the receptacle taken on the line 2—2 of Figure 1.

Figure 3 is a bottom plan view of the cover showing the tray holder or guide frame applied thereto.

Figure 4 is a fragmentary sectional view, somewhat enlarged, bringing out more clearly the manner of engagement of the spring members that hold the tray holder and window glass in position.

Figure 5 is an inverted view of the tray holder or guide frame, dotted lines showing the tray partially extending from the holder as when it may be desired to sell the contents of the said tray.

Figure 6 is a perspective view of the tray.

The present invention is a very simple construction constituting an attachment feature in conjunction with an ordinary cookie, cake, or cracker, display box. This display box or receptacle usually comprises a cardboard carton A at the top of which is applied a detachable frame 1, conforming with the shape of the carton box A. The top of the carton or box A will be removed and in lieu thereof, the frame 1 is mounted upon the top portion of the box thus opened, said frame 1 carrying a cover 2 which consists merely of an open frame thus providing a windowed opening, the window consisting of a piece of glass or transparent substance, designated 3, and seen best in Figures 2 and 4. The cover 2 will be hinged to the frame 1, as at 4, by means of small strap hinges.

The display feature of the invention comprises the approximately square holder B, which is designed to be suspended from the windowed opening of the cover 2, just beneath the window 3. Said holder B is, practically speaking, a guide frame closed at three of its sides and open at 5, as seen in Figure 5, to best advantage. The opening at 5 is at one side of the holder B, and permits of the introduction and removal of the tray C which is in the form of a cardboard carton having partitions 6 whereby to divide the tray into cells. In general form, the tray C is square, and thus conforms with the general square configuration of the holder B which forms the guide frame of said tray.

The said guide frame or holder B is suspended from the windowed opening of the cover 2 by means of flanges 7 at opposite upper edges thereof, the frame structure of the holder B being also equipped with flanges 8 similar to the flanges 7 and lying in the same plane, namely, that of the upper edge of the holder. The pur-

pose of the flanges 7 is to provide interengaging means between the spring wire engaging members 9 attached to the cover, and which engaging members 9 extend beneath the glass or transparent window 3 so as to hold the same in place against the frame of the cover 2.

By reason of the availability of the spring engaging members 9 beneath the window 3, I find that it is very easy to apply the holder B 10 to the cover 2 beneath the window by simply interengaging the flanges 7 between the parts 9 and the window 3, the several flanges 7 and 8 lying flat against the window to afford a flat bearing of the holder B against part 3. It is by 15 reason of this cooperation that I have a readily attachable and detachable holder for the windowed opening of the cover 2, which holder, of course, constitutes the guide frame for the tray C that is readily slidable in a plane parallel with 20 the cover 2 so as to move the tray into the holder and out of the same.

The frame of the holder B is equipped with not only the flanges 7 and 8, which flanges extend outwardly, but said holder is formed in 25 with the inwardly extending flanges 10 at its lower-most portion upon which the bottom of the tray C is adapted to ride in the sliding movement thereof, and to be supported when the tray is stationary on the cover, as will be its normal 30 condition.

With the foregoing in view, it will be seen that the holder B and the tray C when mounted on and combined with the cover 2 of the display receptacle A afford a display feature for the 35 cakes, and cookies, or crackers, or whatever may be the articles to be vended from the receptacle A. The display feature gives the impression that the receptacle is full of its usual contents and this impression will continue so long as the 40 contents of the tray C do not have to be used for making ordinary purchases. Should the contents of the receptacle A become so depleted that upon a sale, the salesman has to use some of the contents of the tray C then it is quite easy 45 to pull the tray out, after the manner shown in dotted lines in Figure 3 and add some of the contents, or all of the contents, to make up the required number of articles to be the subject of the purchase.

50 The construction of the cover 2 involving the window 3 and the spring engaging parts 9 is conventional, and constitutes no part of my invention save as combined with the holder B and the tray C and the detail features of these parts.

55 Having thus described my invention, what I claim as new and desire to secure by Letters Patent of the United States, is:—

1. In a display receptacle of the class described, in combination, a main receptacle, a 60 cover mounted thereon and provided with a windowed display opening, a display tray slidably mounted upon said cover at said windowed opening and normally occupying the space beneath said opening, a holder for said tray detachably connected with said cover and open at one side to permit the slidable shifting movement of the tray when the cover is in open position, and manipulatable holding means on the cover for detachably supporting the window and tray holder 65 on the cover.

70 2. In a display receptacle of the class described, a main box for containing a large quantity of cakes, cookies, or the like, a cover for said box, having a windowed opening, a tray holder detachably mounted on the cover beneath said

windowed display opening thereof, said holder comprising a frame including guide flanges on which the tray is supported for sliding movement, said holder being equipped with suspension flanges abutting with the window in said windowed opening, together with manipulative holding means engageably cooperating with said suspension flanges to attach the holder and window to the cover. 75

3. In a display receptacle of the class described, a main box for containing a large quantity of cakes, cookies, or the like, a cover for said box, having a windowed opening, a tray holder detachably mounted on the cover beneath said windowed display opening thereof, said holder comprising a frame including guide flanges on which the tray is supported for sliding movement, said holder equipped with suspension flanges abutting with the window in said windowed opening, together with manipulative engaging members cooperating with said suspension flanges to attach the holder to the cover, said engaging members clamping the suspension flanges against the window of said windowed opening and clamping the window against the 25 body of the cover so that said engaging members hold both the window and the tray holder in place on the cover, said manipulative members being located beneath the cover and accessible upon moving the latter toward open position. 30

4. In a display receptacle of the class described, in combination, a main box or receptacle for containing a considerable quantity of cakes, cookies, or the like, a frame member at the top of said receptacle, a cover hinged to the frame member, said cover embodying an open frame-like body, a glass window seated against the underside of said frame-like body of the cover, an attachable unit adapted to be emplaced in supported relation to the cover and including a tray holder 40 consisting of a frame-like body having members at its upper edge to engage the underside of the glass window near the edges of the frame-like body of the cover, said holder also comprising a frame for holding a display tray beneath the 45 window of the cover, said frame being open at one of its sides to permit sliding of the tray into and out of the holder so that the contents of the tray, normally supported beneath the window of the cover, may be rendered accessible by the sliding movement of the tray to facilitate vention of said contents, and detachable engaging members carried by the cover cooperating with the frame of the holder and with the glass window of the cover to maintain these parts in proper position on the cover, said engaging members being manipulative to facilitate the placing in position of the holder in supported relation to the cover. 50

5. In a display receptacle of the class described, in combination, a main receptacle, a cover 60 mounted thereon and provided with a windowed display opening, a transparent window member engaged with the underside of the cover at said display opening, a tray holder beneath the window member and cover and comprising a frame 65 including guide members to slidably support a tray in the frame and also including suspension flanges engaged with the under-side of the window member, engaging members on the cover detachably cooperating with the said holder and 70 window member to attach these parts to the under-side of the cover immediately adjacent to the window opening, and a tray slidably mounted in the frame of the holder, the said holder being open at one side hereof so as to permit the pulling 75

outwardly of the tray from the frame of the holder for vendition or replenishment of the contents of the tray.

6. In a display receptacle, a main receptacle, 5 a cover mounted thereon for hinging movement, said cover having a windowed display opening, a transparent window member on the under-side of the cover and engaged with the said under-side at the windowed opening, a tray holder underneath the window member and comprising a 10 frame having offset flange members engaging the under-side of the window member, said frame

comprising also guide members on which a tray is slidable, engaging members attached to the cover at opposite portions thereof beneath the window member and cooperative with the window member and the frame of the tray holder to attach these parts detachably in position on the cover, and a tray slidably mounted on the guide members of the frame of the holder, said frame being open at one side so as to permit such sliding movement.
